CLAIM

The ornamental design for the wireless microphone transmitter, as shown and described.

DESCRIPTION

FIG. 1 is an isometric view of the wireless microphone transmitter;

FIG. 2 is a front view of the wireless microphone transmitter;

FIG. 3 is a side view of the wireless microphone transmitter;

FIG. 4 is a rear view of the wireless microphone transmitter;

FIG. 5 is the top view of the wireless microphone transmitter; and,

FIG. 6 is the bottom view of the wireless microphone transmitter.

The details shown in broken lines in the figures are for illustrative purposes only and form no part of the claimed design.
